CLAIM

The ornamental design for a pet wrap harness, as shown and described.

DESCRIPTION

FIG. 1 is a side, front perspective view of a pet wrap harness;

FIG. 2 is a front view thereof;

FIG. 3 is a rear view thereof;

FIG. 4 is a side view thereof;

FIG. 5 is a second side view thereof, opposite of FIG. 4;

FIG. 6 is a top view thereof;

FIG. 7 is a bottom view thereof; and,

FIG. 8 is an in use perspective view thereof.

The broken lines are included for the purpose of illustrating environmental structure and form no part of the claimed design.

The stitching on the pet wrap harness forms part of the claimed design.
